UNITED STATES PATENT OFFICE

149,983

DESIGN FOR A BOAT

Erich S. Swenson, St. Paul, Minn., assignor to
The Flour City Ornamental Iron Company,
Minneapolis, Minn., a corporation of Minnesota

Application May 20, 1946, Serial No. 129,882

Term of patent 14 years

(Cl. D71—1)

To all whom it may concern:

Be it known that I, Erich S. Swenson, a citizen of the United States of America, residing at St. Paul, in the county of Ramsey and State of Minnesota, have invented a new, original, and ornamental Design for a Boat, of which the following is a specification, reference being had to the accompanying drawings, forming part thereof.

Referring to the drawings:

Fig. 1 is a front perspective view of a boat showing my new design;

Fig. 2 is a perspective view as seen from the top and rear; and

Fig. 3 is a side view in perspective.

I claim:

The ornamental design for a boat, substantially as shown.

ERICH S. SWENSON.
